UNITED STATES PATENT OFFICE

153,961

DESIGN FOR A RECORD DISPLAY COUNTER

Simon Malkin, New York, N. Y.

Application April 6, 1948, Serial No. 145,564

Term of patent 14 years

(Cl. D80—2)

To all whom it may concern:

Be it known that I, Simon Malkin, a citizen of the United States, residing at No. 404 East 14th Street, Borough of Manhattan, in the county of New York, city and State of New York, have invented a new, original, and ornamental Design for a Record Display Counter, of which the following is a specification, reference being had to the accompanying drawing, forming part thereof.

Figure 1 is a front perspective view of a record display counter showing my new design; and

Figure 2 is a side elevational view thereof.

I claim:

The ornamental design for a record display counter, substantially as shown.

SIMON MALKIN.
